COMBINATION RADIATOR AND HUMIDIFIER

Harry S. Welsh and William C. Barber,
Rochester, N. Y.

Application March 9, 1934, Serial No. 714,857

6 Claims. (Cl. 237—78)

The object of this invention is to provide a humidifier and a radiator in combination.

These and other objects of my invention will be illustrated in the drawing, described in the specification and pointed out in the claims at the end thereof.

In the drawing:

Figure 1 is a front elevation of the radiator and humidifier, showing the water connections for the humidifier and the electric device for regulating the flow of water, it being understood that the front plate is omitted from Figure 1.

Figure 2 is a vertical section through the radiator on the line 2x—2x of Figure 1, with the front plate shown in position.

Figure 3 is a top plan view of the drip pan.

Figure 4 is a top plan view of the cover plate and the connections by which it is held in place.

Figure 5 is an enlarged sectional view through one of the spray nozzles used to apply water to the humidifier.

Figure 6 shows a modified form of the water supply pipe and the spray nozzles, in which the supply pipe and nozzles are located above the fins and the water is delivered down on the fins from the nozzle.

In the drawing like reference numerals indicate like parts.

In the drawing reference numeral 1 indicates a radiator for radiating heat, through which radiator steam or hot water is intended to circulate. This radiator is made up of a series of upright sections, the two sections on each end being of a standard type such as are generally used in radiation, while the six intermediate sections 2, 2 etc. are of a special type which will be described as follows.

As shown in side elevation in Figure 2, each intermediate section 2 has two long tubes 3 and 4 at the back, and at the front each section has three short tubes at the top indicated by the reference numerals 5, 6 and 7. The short tubes are connected to the long tubes by the connections 8 at the bottom.

In each section a small tube 9 is specially connected to the bottom of the short tube 6 and to the side of the long tube 4. This gives the water or steam a special path of circulation. On this tube 9 is a series of fins 10, 10, the fins being placed thereon at the rate of several to the inch, the width of the fins being preferably two or three times the diameter of the tube. The object of the fins is to the more readily take the heat from the water or steam that circulates through the small tube 9 and radiate it therefrom.

As shown in Figure 1, six of these tubes 9 are provided, all being placed in parallel to each other.

Between each pair of the tubes 9 is placed a spray nozzle 12, which nozzle is shown in enlarged sectional view in Figure 5. Each of these nozzles is mounted on an upright tube 13, which tubes are connected to a horizontal pipe 14 forming a part of the drip pan, which pipe in turn connects to an upright service pipe 15, which goes through the floor, which pipe in turn is connected to a service pipe 16, which is connected to a water supply under pressure.

The spray nozzle 12 comprises an internally threaded sleeve 17 and a cap 18. Inside of this cap 18 is a plug 19 which has a threaded collar 20 thereon, which collar is threaded with a male thread, which thread engages with a female thread on the inside of the cap. This provides for the adjustment of the plug 19 towards and away from the opening 21 in the cap of the spray nozzle. The plug 19 is provided with a slot 22 therein, which can be engaged by a screw driver for the purpose of turning the plug to adjust it.

A sleeve 23 is provided having a male thread 80 on the upper end thereof that also engages with the female thread on the inside of the cap. This sleeve has a closed bottom, as indicated at 24, which bottom has a slot 25 with which a screw driver can be engaged for the purpose of screwing the sleeve into place. This sleeve is slotted with vertical slots, as indicated at 26, it being understood that the water can flow up through the pipe 13 and around the sleeve 23, and between it and the outer sleeve 17, and between the slots 26 into the sleeve, and then on up past the plug 19, and past the mutilated collar 20. The sleeve 23 is also surrounded by a screen 27, which keeps dirt from going through that might otherwise clog up the nozzle. The cap can be removed from time to time for the purpose of cleaning this screen.

In operation, the water will be sprayed through the opening 21 onto a baffle plate 30 which is placed above the spray nozzle, and from there 100 drips down on the fins, from which it is evaporated by the heat furnished thereto through the tube 9. The heat furnished by the tubes of the radiator proper also helps to evaporate the water from the fins. The excess water drops into 105 a drip pan 31, where it is caught, and from which it drains by the tube 32.

It will be noted that the drain tube 32 extends about half way up in the drip pan. This insures the maintenance of a certain water level in the 110

drip pan which adds to the humidifying effect if an excess of water is furnished.

For the purpose of regulating the supply of water to the spray nozzles, we provide a humido-stat 40 and a solenoid valve 45 having electrical connections 41, 42 to a transformer 43, it being understood that any of the standard types of solenoid valves and humidostats and transformers may be used for this purpose. The solenoid valve closes when the humidity of the air in the room reaches the proper amount, and opens again when the humidity falls below that amount. In this way an ample supply of water is furnished to the spray nozzles and insures the keeping of the air in the room at the proper humidity.

It will be understood that the tubes 9 and fins 10 are concealed ordinarily by a plate 50, which is fastened to the radiator by means of the bolts 20 51, 51 which engage with the radiator tubes with suitable washers and nuts, by which the plate is held in place and which permits its easy removal.

The radiator behind this plate forms an evaporating chamber inside of the radiator, which is concealed by the plate 50 and is a part of the radiator, so that the radiator is made to perform both the function of heating the room, together with the humidifying of the air in the room.

30 A needle valve 55 is provided which limits the maximum amount of water that is furnished to the spray nozzles. It will also be understood that in the pipes 15 and 32 unions 56 and 57 are provided which can be disconnected so that the drip pan and the spray nozzles and pipes associated therewith can be removed bodily from the radiator. It will also be understood that the drip pan rests on a base 58 provided in the radiator.

In Figure 6 we have shown a modified form of 40 the nozzle, in which the pipe 60, which is the equivalent of the pipe 14, is placed near the top of the humidifying chamber and is provided with gooseneck nozzles 61, one for each tube 9, which deliver the water directly to the top fin 62 on the 45 tube 9, so that the water can drip from one fin to another and be evaporated in so doing. The radiator section, the tubes 9, and the drip pan etc. will be the same with this modification as has been described above.

50 We claim:

1. A radiator made up of a plurality of upright sections placed parallel to each other, the sections at either end having a plurality of tubes therein extending the full height of the radiator, 55 the intermediate sections having a portion of the tubes on one side cut away between the top and bottom, forming an evaporating chamber that is enclosed on five sides by the radiator sections and tube and is open on one side, a tube in each 60 intermediate section connecting the lower end of one of the cut-away tubes with the uncut full length tube permitting the circulation of water therethrough, fins on said tube to promote the radiation of heat therefrom.

65 2. A radiator made up of a plurality of upright sections placed parallel to each other, each section being made up of a plurality of hollow tubes, the sections at either end having tubes

70

75

extending the full height of the radiator, the intermediate sections having a portion of the tubes on one side cut away between the top and bottom, forming an evaporating chamber therein that is enclosed on five sides by the radiator sections and is open on one side a special tube in each intermediate section connecting the lower end of one of the cut-away radiator tubes with one of the full length tubes permitting the circulation of water therethrough from the one tube to the other, fins on said tubes to promote the radiation of heat therefrom, means for delivering water to said fins to be evaporated therefrom for the purpose of humidifying the air.

3. A radiator made up of a plurality of upright sections, placed parallel to each other, each section being made up of a plurality of hollow tubes, said sections having a portion of the tubes on one side cut away between the top and bottom forming an evaporating chamber therein, a special tube in each section connecting the lower end of one of the cut-away radiator tubes with one of the full length tubes, permitting the circulation of water therethrough from the one radiator tube to the other.

4. A radiator made up of a plurality of upright sections, placed parallel to each other, each section being made up of a plurality of hollow tubes, said sections having a portion of the tubes on one side cut away between the top and bottom forming an evaporating chamber therein, a special tube in each section connecting the lower end of one of the cut-away radiator tubes with one of the full length tubes, permitting the circulation of water therethrough from the one radiator tube to the other, fins on said tubes to promote the radiation of heat therefrom, means for delivering water to said fins to be evaporated therefrom for the purpose of humidifying the air.

5. A radiator made up of a plurality of upright sections, placed parallel to each other, each section being made up of a plurality of hollow tubes, said sections having a portion of the tubes on one side cut away between the top and bottom forming an evaporating chamber therein, a special tube in each section connecting the lower end of one of the cut-away radiator tubes with one of the full length tubes, permitting the circulation of water therethrough from the one radiator tube to the other, a drip pan located under said special tubes, the lower portion of the cut-away sections forming a base that supports the drip pan.

6. A radiator made up of a plurality of upright sections, placed parallel to each other, each section being made up of a plurality of hollow tubes, said sections having a portion of the tubes on one side cut away between the top and bottom forming an evaporating chamber therein, a special tube in each section connecting the lower end of one of the cut-away radiator tubes with one of the full length tubes, permitting the circulation of water therethrough from the one radiator tube to the other, fins on said tubes to promote the radiation of heat therefrom, spray nozzles for delivering water to said fins.
